CURTAIN

Richard F. Loeb, Jenkintown, Pa.

Application May 18, 1945, Serial No. 594,545

4 Claims. (Cl. 160—124)

This invention relates to what are known as criss-cross curtains. Heretofore this type of curtain has also been commercially known as "cottage curtains" and under that designation are formed of two curtain units arranged in overlapping relation to each other and permanently sewed together with a single continuous heading formed at their upper ends for reception of a single supporting rod.

Cottage curtains, when hung at a window are separated at their lower ends and are drawn laterally in opposite directions and held in draped folds by cords, or bands of the curtain material, known as "draw-backs," which are attached to the opposite side rails respectively of the window frame.

Curtains of the above-noted type are usually made in various predetermined overall widths, to fit certain sizes of windows, with enough excess in the width of the curtain to permit the curtain, as a whole, to be bunched along the curtain rod in loose soft pleats to enhance the appearance thereof, however, no provision was made for adjusting the curtain units relative to each other with respect to the degree of overlap therebetween which has been a disadvantage responsible for a more or less limited demand for this type of window hanging.

In order to overcome the aforesaid disadvantage, some housekeepers have used two identical separate and distinct curtain units respectively supported on and hanging from a pair of closely positioned, horizontally adjacent parallel rods, with one curtain unit slidably mounted on the "front" rod, adjacent one side rail of the window frame, and the other curtain unit slidably mounted on the "back" rod, adjacent the opposite side rail of the window frame.

The above arrangement permits maximum latitude in adjusting the curtain units relative to each other and to the side rails of the window frame and permits the housekeeper to obtain any degree of overlap of the upper portions of the curtain units as may be desired, but, with this arrangement, there is always a portion of the front rod which is not covered or hidden by any portion of either of the curtain units, and this exposed portion of the front rod spoils the esthetic effect of the entire window hanging.

Now, the principal object of the present invention is to provide a pair of curtains which are adapted to be hung on separate front and back rods respectively to afford the above-noted maximum degree of relative adjustability therebetween, without at any time having any portion

of the front rod exposed to view and with that portion of the back rod which is not encased in the heading of the curtain unit hanging therefrom, hidden from view by the unit on the front rod.

More specifically, one object of the invention is to provide each or one of a pair of curtain units with a lateral extension including a heading for encasing that portion of the front, and if desired the back curtain rod which normally would otherwise be left bare when using separate curtain units on separate rods as criss-cross curtains.

And still another object of the invention is to provide a curtain unit with a rod-receiving heading of its own and a lateral extension constituting an integral part thereof and provided with a rod-receiving heading in contiguous alignment with the heading of said unit; and to provide such unit and integral lateral extension with a valance extending the entire width of the said curtain unit and the said lateral extension, thereby affording the appearance of a coordinated whole.

The construction and mode of operation of the curtain will be fully disclosed hereinafter, reference being had to the accompanying drawing of which:

Fig. 1 is a perspective view illustrating the preferred embodiment of the invention;

Fig. 2 is a sectional view taken on the line 2—2 of Fig. 1;

Fig. 3 is a sectional view taken on the line 3—3 of Fig. 1; and

Fig. 4 is a schematic pattern view of the pair of curtain units which make up the criss-cross curtain illustrated in Fig. 1.

Referring more particularly to the drawing, the pair of curtain units which make up the criss-cross curtain A of the present invention are indicated at 1 and 2, in Fig. 1, which shows said curtain units in operative relation to each other. The curtain unit 1 is provided with a lateral extension 3 which are, collectively, adapted to extend across the full width of the window before which the curtain is hung and the entire length of the front curtain rod 4 on which the unit 1 and its lateral extension 3 are mounted to obviate the non-esthetic appearance of the prior art curtains wherein a large portion of the front curtain rod was left bare and barren. On the back curtain rod 5, is draped the second unit 2 of the two units of the criss-cross curtain A, so that cooperatively the two curtain units 1 and 2 form a substantially triangular opening 6 when

these units are respectively drawn back and held by draw-back bands B, B as shown in Fig. 1, for observation through the adjacent window. The two criss-crossed units form another closed triangle 7 with one corner portion 8 of the back unit 2 hidden from view by the overlapping corner portion 9 of front curtain unit 1.

By such construction the triangle opening 6 may be made large or small as desired, by merely adjusting of the respective curtain units along their respective curtain rods, and yet at no time in the course of such adjustment nor when completed will the artistic appearance of the curtain A as a whole be adversely affected, due to the laterally extended portion 3 of the front curtain unit 1, as the front curtain rod will at all times be completely covered and thus never presents a bald display to the observer.

As shown in Fig. 4 the curtain units 1 and 2 are of substantially equal dimensions, the curtain unit 1 having in addition the laterally extended portion 3, said curtain unit and its lateral extension being formed or fabricated as one piece.

The units 1 and 2 are provided with rod-receiving headings 10 and 11 respectively and which are in the form of tubular hems, and the lateral extension 3 of the unit 1 is provided with a similar heading 12 continuous with the heading 10 of the unit 1 for reception of the rod 4.

To improve the esthetic effect of the curtain as a whole, the unit 1 and its lateral extension 3 are provided with a continuous double ruffle extending above and below the headings 9 and 11 thereof in the form of a valance 15. The curtain unit 1 and its lateral extension 3 are placed upon the front curtain rod 4, so that the headings thereof will collectively cover said rod 4 entirely, and since combined widths of the unit 1 and its extension 3 are greater than the length of the rod 4, the valance 15 will assume a softly pleated and ruffled appearance, as shown in Fig. 1.

The curtain unit 2 is placed on the back curtain rod 5, said curtain unit 2 will extend beyond the inner edge of the curtain unit 1 so that there results an overlapping of curtain unit 1 in front of the curtain unit 2, thus forming what is known in the art as a cross-cross curtain A.

Due to the aforesaid overlapping, when the two curtain units 1 and 2 are draped, as by pulling the inner side edges of the two units inwardly and holding them in such relation as shown in Fig. 1 by means of draw-back bands B, B, there is formed the triangular opening 6 for an observer, and the triangular criss-crossing of the top portions of the curtains, as indicated at 7. Thus, whether in an open or closed relationship, the front rod 4 is at all times covered by the curtain unit 1 and its lateral extension 3, and the valance 15, which covering obscures from view the otherwise uncovered portion of the front rod so that an artistically integrated whole is presented to view from within the room in which the curtain A is installed.

It is also to be noted that one curtain unit having the lateral extension as a part thereof may be used at a window without using the other

second curtain unit therewith and still present a pleasing appearance, due to the complete coverage of the curtain rod on which the first said unit and its lateral extension are mounted. By such use, for example, there may be two adjacent windows having a single curtain rod or double rod extending across the combined widths of both windows, each of said windows could be partly or wholly covered by a curtain unit having a lateral extension with the respective units proper being draped at opposite sides of the combined adjacently disposed windows and the lateral extensions of the units lying adjacent each other, a very artistic appearance would result, so that the two curtains could take the place of four while the entire curtain rod structure would be completely covered.

I claim:

1. A criss-cross curtain comprising a pair of curtain units adapted respectively to receive and hang down from a pair of laterally and horizontally spaced substantially parallel front and back curtain rods, and a lateral extension on at least one of said curtain units adapted collectively to cover the entire length of the curtain rod upon which such unit and its lateral extension are mounted, said curtain units and extensions being slidably movable on said curtain rods.
2. A criss-cross curtain comprising a pair of curtain units adapted to be slidably mounted upon laterally spaced substantially parallel curtain rods, a lateral extension on and forming a part of at least one of said curtain units and adapted in cooperation with said one curtain unit to completely cover the outermost of said curtain rods, and a valance forming a part of said curtain unit and said extension and extending across the combined widths thereof.
3. A criss-cross curtain comprising a pair of curtain units adapted to be slidably mounted upon laterally spaced substantially parallel curtain rods, a lateral extension on and forming a part of at least one of said curtain units and adapted in cooperation with said one curtain unit to completely cover the outermost of said curtain rods, contiguous tubular headings formed in said one unit and its lateral extension respectively for receiving the curtain rod on which said one unit and its lateral extension are mounted, and a valance forming a part of said curtain unit and said extension and extending across the combined widths thereof.
4. A criss-cross curtain comprising a pair of curtain units adapted respectively to be mounted on a pair of laterally spaced substantially parallel front and back curtain rods, a lateral extension of the unit mounted on said front rod and adapted in cooperation with said curtain unit to extend over and completely cover said front curtain rod, said units being adapted to be drawn back to form a triangular overlap of said units in the upper portions thereof adjacent said curtain rods, said triangular overlap being adapted to be varied in size by relative adjustability of said curtain units on their respective rods while maintaining the appearance of an integrated whole.
